UNITED STATES PATENT OFFICE.

FRANK R. OWENS, OF BEAVER CROSSING, NEBRASKA.

PUMP JACK.

Application filed April 29, 1925, Serial No. 26,736. Renewed March 2, 1926.

To all whom it may concern:

Be it known that I, FRANK R. OWENS, a citizen of the United States, residing at Beaver Crossing, in the county of Seward 5 and State of Nebraska, have invented new and useful Improvements in Pump Jacks, of which the following is a specification.

This invention relates to improvements in pump jacks, the general object of the 10 invention being to provide an equalizing device for the reciprocating member to provide an even movement of the pump rod.

Another object of the invention is to make the parts adjustable so that a spring 15 of the desired strength can be used with the device.

This invention also consists in certain other features of construction and in the combination and arrangement of the several 20 parts, to be hereinafter fully described, illustrated in the accompanying drawings and pointed out in the appended claims.

In describing my invention in detail, reference will be had to the accompanying 25 drawings wherein like characters denote like or corresponding parts throughout the several views, and in which:

Figure 1 is an elevation showing the invention in use.

30 Figure 2 is a view looking at right angles to Figure 1.

Figure 3 is a section on line 3—3 of Figure 1.

Figure 4 is a section on line 4—4 of Figure 1.

Figure 5 is a section on line 5—5 of Figure 1.

Figure 6 is a section on line 6—6 of Figure 1.

40 Figure 7 is a sectional view through the upper cross piece and showing a portion of the pump rod passing through the same.

In these views A indicates the cylinder in which the device is arranged which reciprocates the rods 1 which are connected with the lower cross piece 2 and the upper cross piece 3. This device forms the subject matter of a patent granted to me on December 16, 1924 No. 1,519,926. In this 50 patent I make use of a weight for helping the device to lift the pump rod, and it is the object of the present invention to substitute spring means for this weight. Such means comprises an angle bar 4 having its 55 forked end 5 fastened to the cross piece 3

and a second angle bar 6 pivoted to an upright 7 on the cylinder A and having one arm of fork-shape, as shown at 8, to receive an arm of the bar 4, the two parts being pivoted together by the pin 9 which is adapted to engage any one of a plurality of sets of holes 10 formed in the parts so that the two angle bars can be adjustably connected together. The bar 6 can also be adjusted on the upright 7 by means of the 60 pivot pin 11 engaging any one of a number of holes 12 in said upright. This bar 6 has a depending part 13 thereon which has an eye at its lower end through which a bolt 14 passes which is carried by the upright 7 and has a spring 15 thereon which balances the weight of the bar 6. The bars 4 and 6 are provided with notches 16 on the outer edges for receiving the clips 17 to which a spring 18 is connected, the notches 70 permitting the clips of the spring to be adjusted on the bar.

As will be seen, the spring tends to hold the bars 4 and 6 in parallel position, as shown in Figure 1, but on the down stroke 80 of the pump the arms will spread apart and thus tension the spring so that the spring will help the device to lift the pump parts on the up-stroke. Thus the spring will take the place of the weight shown in 85 the patent above referred to and the device will act to equally divide the power of the operating device for the pump on the up and down strokes and provide an even movement of the pump rod. By making 90 the parts adjustable springs of different strength can be used to suit the work being done.

It is thought from the foregoing description that the advantages and novel features 95 of my invention will be readily apparent.

I desire it to be understood that I may make changes in the construction and in the combination and arrangement of the several parts, provided that such changes fall 100 within the scope of the appended claims.

Having thus described the invention, what is claimed as new, is:

1. An equalizing device for a pump operating apparatus comprising an angle bar 105 connected with a reciprocating part of the apparatus, a supporting bar of angle shape to which the first bar is pivoted, a spring connecting the two bars together, means for adjusting the parts to enable springs of 110

different strength to be used, and a counterbalanced spring for the supporting bar.

2. An equalizing device for a pump operating apparatus, comprising a support, a supporting bar of angle shape having one limb pivoted to the support, an angle bar having one limb adjustably pivoted to the

other limb of the supporting bar and its other limb connected with a reciprocating part of the apparatus, a spring connecting the parallel portions of the two bars together. 10

In testimony whereof I affix my signature.

FRANK R. OWENS.
